UNITED STATES PATENT OFFICE.

CARLISLE FORREST SMITH, OF JERSEY CITY, NEW JERSEY, ASSIGNOR TO BOURNONVILLE ROTARY VALVE MOTOR COMPANY, OF HOBOKEN, NEW JERSEY, A CORPORATION OF NEW JERSEY.

ROTARY VALVE.

Application filed June 19, 1922. Serial No. 569,478.

To all whom it may concern:

Be it known that I, CARLISLE FORREST SMITH, a citizen of the United States, and a resident of Jersey City, in the county of 5 Hudson and State of New Jersey, have invented a new and useful Rotary Valve, of which the following is a specification.

The invention relates to rotary valves and particularly to rotary-valves controlling the 10 intake and exhaust of internal combustion engines.

An important object of the invention is to provide a construction which is simple to manufacture and causes the valve to be at 15 all times tight and to accommodate itself to expansion and contraction and wear, at the same time insuring true bearing for the valve member under all variations.

The valve involves a novel compensating 20 device possessing a floating shoe, which is supported tiltingly, and yet rigidly, or substantially rigidly, against radial force, so as to move circumferentially of the valve member in order to move radially to vary the 25 effective diameter of the casing, this shoe being guided in its circumferential movement directly by the curved surface of the valve member itself.

In the accompanying drawings illustrating 30 the invention:

Fig. 1 is a vertical transverse section through an engine embodying the invention, the engine illustrated being of a general type disclosed in numerous prior 35 patents issued to Eugene M. Bournonville;

Fig. 2 is a section on the line 2—2 of Fig. 1; and

Fig. 3 is a plan view of a slide member.

The numeral 1 designates a cylinder block, 40 and 2 a separate head, the parting or joint being marked 3. The engine will naturally be understood as comprising a plurality of cylinders, of which the one in the plane of the section is marked 4. The head and the 45 adjoining portion of the cylinder block together form a casing for a rotary cylindrical valve member or plug 5, which extends longitudinally over the tops of the cylinders, preferably in two or more flexibly 50 jointed sections as is familiar.

This valve casing contains an incomplete cylindrical bore 6, at the bottom of which is a port communication 7 to the combustion chamber 8 of the cylinder, while at 55 opposite sides are an intake manifold and

port 9, 10 and an exhaust port and passage 11, 12. The cylindrical bore curvature includes these several ports and preferably extends above the central horizontal plane of the valve member. The valve member 60 is formed with pocket ports 13 in its sides which are properly positioned to connect the cylinder port 7 alternately with the intake and the exhaust at the proper times. The valve is suitably connected with the 65 crank-shaft to rotate always in one direction, the direction of rotation being indicated by the arrow.

Owing to the novel construction which is about to be described, the fixed bore and the 70 valve member can be made with a substantial clearance (still too small, of course, to illustrate), which is a great advantage for manufacturing purposes. The valve is nevertheless held tight against leakage and 75 in opposition to the pressure in the cylinders, while being enabled to expand without binding and to contract without loss of power. This is accomplished by means of the novel compensating device the preferred 80 form of which will now be described.

The portion 14 of the valve chamber above the fixed bore and opposite the port 7 is formed to accommodate a shoe 15, or mobile part of the casing, having a segmental under face substantially conforming to a considerable portion of the cylindrical surface of the valve member, it being understood, of course, that the curvature of the shoe like that of any bearing is of somewhat 90 greater radius than the rotating member. Above, that is to say, back of, the shoe, at the top of the chamber 14 is a straight transverse, inclined, rigid way or slide surface 18, against which the shoe is supported 95 through the intermediary of a slide or wedge 16 having a sloping back 17 affording an extended sliding surface. The shoe and wedge will be understood as suitably extended lengthwise of the valve, but it will be observed that the slope or taper of the wedge 100 is transverse to the shoe and valve and contrary to the direction of rotation of the valve member, the slope being at a low angle to the line or tangent which is at right angles to 105 the central line passing through the port 7, the center of the valve member and through or near a rocker joint or point of tilting support, the preferred form of which will now be described. A half-round longitudinally 110

extending rib 19 on the back of the shoe intermediate its sides and a corresponding groove in the straight front or under face of the wedge form an articulation or rocker, 5 its axis parallel with the axis of the valve, which permits the shoe to have slight angular movement so as to bear truly at all times against the valve member, there being sufficient room between the shoe and wedge and 10 between the sides of the shoe and the chamber for this purpose, and also to permit slight bodily movement, the shoe thus floating on and being guided circumferentially by the valve surface itself. A spring 20 in 15 a spring-chamber 21, backed by a screw plug 22, presses against the large end or side of the wedge. In practice there are preferably two or more of these springs acting upon the wedge at spaced points. The spring means 20 opposes the circumferential movement of the shoe in one direction and presses the shoe against the valve member and the latter to its seat in the fixed bore. The slope of the wedge and wedge-way is too low to permit the 25 wedge to yield to the force of the explosions or of the compression or the exhaust, the wedge being self-holding in this respect. If, however, the valve tends to stick owing to expansion, the increased frictional drag 30 of the valve member on the shoe transmitted through the articulation or toggle forces the parts slightly against the springs and thereby automatically relieves the condition. Slight radial movement of the shoe, 35 in or out with respect to the center of the valve, is thus obtained by virtue of true circumferential movement in one direction or the other. The springs are of such strength as to resist normal frictional drag sufficiently to secure the desired tightness. 40

The articulation 19 affords a gas barrier which prevents leakage past it from the intake side to the exhaust side of the valve. The bearing of the shoe upon the valve 45 member and of the back of the wedge upon the surface 18 is likewise gas tight.

Lubricating oil is supplied from a suitable source through a duct 29 which passes downward through the top of the valve casing and has its lower end delivering through the inclined face 18 in communication with a channel 30 in the inclined back of the wedge, this channel running lengthwise with respect to the valve, and being located 50 near the high portion of the downward slope. The oil passes along this channel and is distributed from it by suitable cross grooves 31 running down the slope of the wedge. In this way the sliding surfaces of the wedge and way are lubricated, and the lubricant then passes downward over the thin end or side of the wedge and past the shoe to the valve itself, so that the surfaces 55 of the rotary valve member and of the fixed portion of the bore and the curved face of

the shoe are kept lubricated, all in a very simple and efficient manner.

From the foregoing it will be perceived that I have provided a construction which is highly advantageous both for production 70 and in operation. The compensating device as herein illustrated comprises a two-part movable structure consisting of the entirely free and mobile shoe and a movable backing part, represented by the slide or wedge, 75 the two connected by a central rocker which enables the shoe to tilt and follow the curvature of the valve member while the other part executes a different movement. I deem this the best and most practical embodiment, 80 but do not necessarily limit myself thereto as the shoe may be movably and tiltingly supported on a transverse backing guide in other ways. The complete mobility of the shoe enables it to adjust itself perfectly to 85 any condition that may arise.

It will be understood that the term "rotary valve" used herein refers to a valve which rotates always in one direction.

What I claim as new is:

1. A rotary valve comprising a rotary valve member, a casing, a compensating device having a mobile shoe movable circumferentially and thereby radially of the valve member, and backing means whereby the 90 shoe is completely supported at a central region so as to be free to tilt as it is guided circumferentially on and by the curved surface of the valve member.

2. In a rotary valve having a rotary valve 100 member and a casing, a shoe bearing on the valve member, means backing the shoe and permitting the same to relieve the valve member through movement in the direction of rotation of the valve member, and means 105 opposing the drag of the valve member on the shoe and tending to move the shoe in the reverse direction to take up clearance, the shoe being free to tilt on the backing means and floating circumferentially on the valve 110 member.

3. In an internal combustion engine, the combination with a combustion chamber and a valve casing having a port communicating with the combustion chamber, of a rotary 115 valve member in the casing, a shoe having a segmental face bearing floatingly on the valve member opposite said port, means including a backing whereby the shoe is supported against radial force and rendered responsive to the drag of the valve member so 120 as to move outward or inward with respect thereto, and means whereby the shoe is centrally supported to rock on the backing.

4. In a rotary valve having a rotary valve 125 member and a casing, an automatic compensating device comprising a two-part movable structure having its parts connected by a rocker joint, one of the parts being a shoe the face of which obediently follows the con- 130

tour of the valve member while the other part executes a different movement to cause simultaneous slight recession or approach of the shoe.

5. In a rotary valve having a rotary valve member and a casing, an automatic compensating device comprising a backing guide or way and a two-part movable structure having its parts connected by a rocker joint, one 10 of the parts being a shoe the face of which obediently follows the contour of the valve member while the other part slides in a different path on the backing guide.

6. In a rotary valve having a rotary valve member and a casing, an automatic compensating device including a shoe bearing on the valve member and having a rocker at its back, and a backing guide or way inclined at a low angle to a line at right angles to the 20 line passing through the centers of the valve member and rocker, the shoe being free to tilt while performing its compensating functions.

7. In a rotary valve, the combination with 25 a valve casing containing an incomplete ported bore, and a rotary valve member therein, of a shoe in the casing bearing upon the curved surface of the valve member, a wedge and wedge-way back of the shoe 30 tapered contrary to the direction of rotation of the valve member, the wedge and shoe being articulated so that the shoe may always bear truly upon the valve member, and spring means opposing movement of the shoe 35 and wedge under the drag of the valve member.

8. In a rotary valve, the combination with 40 a valve casing containing an incomplete ported bore, and a rotary valve member therein, of a shoe in the casing bearing upon the curved surface of the valve member, a wedge and wedge-way back of the shoe 45 tapered contrary to the direction of rotation of the valve member, the wedge and shoe being articulated so that the shoe may always bear truly upon the valve member, and spring means acting upon the wedge in opposition to the drag on the valve member of the shoe.

50. 9. In a rotary valve, the combination with a valve casing containing an incomplete ported bore, and a rotary valve member therein, of a shoe in the casing bearing upon the curved surface of the valve member, a 55 way and a movable member backing the shoe, said movable member having a rocker connection with the shoe whereby the shoe may move circumferentially and radially of the valve member while always bearing truly 60 upon the valve member, and means opposing the drag of the valve member upon the shoe and tending to hold the valve tight.

10. In a rotary valve, the combination with 65 a valve casing containing an incomplete ported bore, and a rotary valve member

therein, of a shoe in the casing bearing upon the curved surface of the valve member, a 70 movable member backing the shoe, an articulation between said member and shoe comprising a longitudinal rib on one cooperating with a groove in the other, and spring means opposing the drag of the valve member upon the shoe and tending to hold the valve tight.

11. In an engine valve, the combination of 75 a valve casing presenting a curved valve seat, a rotary valve which turns in one direction therein, a shoe bearing upon the top of the valve, a wedge-way at the top of the casing sloping transversely downward contrary to the direction of rotation of the valve, a wedge having its sloping face in contact with said wedge-way, a rocker articulation connecting the wedge and shoe, 80 spring means opposing the drag of the valve member on the shoe, and means for supplying lubricant between the sliding faces of the wedge and wedge-way and thence to the valve.

12. In a rotary valve, a rotary valve 90 member, a casing having an incomplete bore for said valve member and a slide surface outside the radius of the bore, a mobile shoe bearing floatingly upon the top of the valve member, and movable circumferentially 95 thereof, a member having a rocker articulation with said shoe and slide on said slide surface with the circumferential movements of the shoe to vary the distance between the shoe and the axis of the valve, means for 100 yieldingly opposing the movement of the shoe and slide member under the drag of the valve member, and means for supplying lubricant between the slide member and the slide surface of the casing and thence to 105 the surfaces of the valve member and bore.

13. In a rotary valve, the combination of 110 a rotary valve member, and a compensating device comprising a transverse backing guide and a shoe responsive to the drag of the valve member, said shoe being supported centrally by said backing guide so as to be free to tilt in order to be guided circumferentially by the valve member, substantially as described.

14. In a rotary valve, a casing having a port, a rotary valve member, and a compensating device comprising a shoe bearing on the curved surface of the valve member, a transversely movable slide backing the shoe, the shoe and slide having a rocker joint, a transverse backing guide for the slide sloping at a low angle to a line at right angles to the central line passing approximately through the port, the rocker joint and the center of the valve member, and means urging the slide and shoe in opposition to the drag of the valve member.
